LAURENCE E. BLACKMAN, OF HARTSVILLE, SOUTH CAROLINA

FLOAT PREVENTER FOR LOOMS

Application filed December 24, 1929. Serial No. 416,252.

This invention relates to a float preventer for looms and more especially to an improvement in stop motion which is adapted to automatically stop the loom when a float occurs. A float is defined as the shuttle failing to follow its proper course between the warp threads, due to the fact that when the warp becomes too taut in certain spots that it will cause the shuttle to float on the wrong side 10 of the warp and cause the respective threads to be woven improperly.

An object of my invention is to provide means for automatically stopping a loom when the warp is tangled for any reason.

Another object of my invention is to provide means for automatically stopping a loom when the take-up roll or the let-off roll does not function properly to preserve the proper tautness in the warp. My invention is adapted to cooperate with the regular stop motion on a loom, but as a regular stop motion on a loom does not function to stop the loom when the warp threads become too taut, but on the other hand functions to stop the loom when 20 the warp threads become too loose or become broken. It is an object of my invention to provide means adapted to be associated with the regular stop motion of the loom whereby the loom will be automatically stopped when 25 the warp threads become too taut at any point therein due to any reason whatsoever.

Another object of my invention is to provide means for automatically stopping the loom when the shuttle is not thrown clear 30 through the warp or flies out of the warp at any point.

When the take-up roll stops operating the warp and cloth becomes loose and, therefore, stoppage of the loom will occur on account 35 of the fact that the inertia of the stop motion members causes them to fly upwardly when they are raised quickly and, therefore, operating to release one or more drop wires to stop the loom.

Some of the objects of my invention having been stated other objects will appear as the description proceeds, when taken in connection with the accompanying drawings, in which—

Figure 1 is a transverse view through a

loom showing my invention applied to one type of stop motion;

Figure 2 is a cross-sectional view through the stop motion mechanism shown in Figure 1;

Figure 3 is a perspective view of a special bracket in which my stop motion means are mounted;

Figure 4 is a cross-sectional view taken along the line 4—4 in Figure 1;

Figure 5 is a view looking from the right-hand side of Figure 4;

Figure 6 is a perspective view of the upper portion of Figure 4;

Figure 7 is a perspective view of one of the parts of my stop motion;

Figure 8 is a perspective view of the drop wire in my stop motion;

Figure 9 is a cross-sectional view taken along the line 9—9 in Figure 4;

Figure 10 is a view similar to Figure 1 but showing a slightly different form of stop motion applied to another type of loom;

Figure 11 is a cross-sectional view taken along the line 11—11 in Figure 10;

Figure 12 is a view of the upper left-hand corner of Figure 10;

Figure 13 is an end view of Figure 12 looking from the line 13—13 in Figure 12;

Figure 14 is a perspective view of the drop wire in this type of stop motion for float preventers;

Figure 15 is a perspective view of the wire adapted to release the drop wire;

Figure 16 is a perspective view of the mounting for the structure shown in Figures 14 and 15;

Figure 17 is a view of the upper portion of Figure 11 looking from the same side but on a large scale;

Figure 18 is a perspective view of the upper central portion of Figure 17;

Figure 19 is an edge view of Figure 17 looking from the right-hand side thereof;

Figure 20 is a cross-sectional view taken along the line 20—20 in Figure 19.

Referring more specifically to the drawings the numerals 10 and 11 indicate the frame portion of a loom and the numeral 12 indicates a transversely disposed brace bar

which is mounted in close proximity to the stop motion mechanism of the loom. Secured at each side of the loom in the upper portions of members 10 and 11 is a conventional channel bar 13 in which a bar 14 is adapted to slide, the channel bar 13 having notches 15 therein, and the bar 14 having notches 16 therein. As is well known in the art this is a conventional type of stop-motion and has a plurality of drop wires mounted thereon, which drop wires are not shown in this application, as these drop wires are conventional, and there is one drop wire for each thread, and some of these drop wires are mounted on one of the sets of members 13 and 14, and some are mounted on the other sets of members to prevent crowding the same all on one member as would be practically impossible due to the great number of warp threads, at one end of the members 13 and 14 a conventional stop-motion mechanism is mounted and this comprises a slot 17 in the channel member 13 and the sliding notched bar 14 has the member 18 pivotally secured thereto as at 19, and this member 18 is pivotally secured as at 20 to a member 21 which in turn has a pivotal and sliding connection with the feeler bar finger strip 21a which is adapted to press against plunger fingers 22, which presses against plunger 23 which is mounted in the flexible cable 24 and a plunger housing 25 is secured in a rocker or oscillating arm 26 which is pivotally mounted as at 27, and an oscillating lever 28 is connected to a rod 29 which extends to a portion of the loom so as to give this a continuous rocking motion. The plunger bar 23 leads to the means for stopping a loom, and in most instances this leads to the shipper lever mechanism for stopping the loom. The showing of the same is not deemed necessary as it is the conventional stop motion means in a loom.

The mechanism thus far described is the conventional stop motion loom mechanism on one type of loom, and it is with this type of mechanism that I propose to mount my float preventing means. These float preventing means are shown in Figure 4 wherein four identical float preventing means are shown as being secured on the bar 12, but I desire it to be understood that any number of float preventing means would operate such as two or three or five or any desired number located along the bar 12 as will be later explained.

My mechanism comprises the bracket 30 which has the flange 31 thereon, through which holes 32 appear and in these holes 32 screws 33 are placed which penetrate threaded holes in the bar 12 to secure this bracket 30 in position. This bracket 30 has the upstanding portion 34 which has the channel portion 35 at one edge thereof with a hole 36 punched through the upper portion thereof of which hole is punched on three sides and the lip 37 is turned outwardly to form a pro-

jection with the inwardly sloping shoulder 40 on the upper portion thereof to normally hold the drop wire of my float preventing mechanism in position. Slidably mounted in the channel 35 is the slide member 41 which has the cut-away portion 42 which coincides with the cut-away portion 43 in the channel portion 35. This cut-away portion 42 and the cut-away portion 43 are present in order to enable the channel bar 13 and the sliding bar 14 to occupy this space immediately beneath a cut-away portion 45 in a member 46 which is adapted to have the portion 47 normally in engagement with the inwardly sloping shoulder 40 on the upper portion 34 of member 30. This member 46 also has the downwardly projecting portion 48 which has an inwardly sloping shoulder portion 49 to cause the same to properly engage the bars 13 and 14 when the same is released from the member 37. This member 46 is slidably mounted along the surface 50 of the channel 35 and is held in position loosely by means of guards 51 and 52 which are brazed, welded or otherwise secured to the channel members 35. The member 41 is adapted to slide in channel 35 and this member 41 has a projection 56 extending therefrom with the outwardly sloping shoulder portion 57, said projection 56 extending through the hole 36 in the channel portion 35, and this member 41 has a slot 55 therein through which a rod 58 is adapted to pass, and the warp threads 59 are adapted to pass beneath this rod 58 and when any portion of the warp threads becomes too taut for any reason, this rod 58 will be pulled upwardly to the dotted line position 60 shown in Figure 2, and this will raise member 41 and cause the member 56 thereon in cooperation with shoulder 57 to raise the member 46 upwardly and force it off of the inwardly sloping shoulder portion 40 and cause the same to fall downwardly until the portion 45 engages the notches 15 and 16 in the relatively sliding members 13 and 14 to operate the conventional stop-motion mechanism to stop the loom.

In Figures 10 to 20 inclusive I have shown a slightly modified form of my invention as applied to another type of loom. Some looms have the serrated bar stop-motion as previously described which is known as the #17 Stop motion, and other looms have a different type of stop motion which is operated by an oscillating bar extending all the way across the loom between fixed bars with transversely disposed bars, on which the drop wires of the conventional stop motion are mounted, so that when a thread breaks the drop wires will drop down between the fixed bar and the oscillating bar and prevent its full swing and operate a stop motion mechanism, due to the fact that a cam on the drive shaft will fail to pass the projection asso-

ciated with the oscillating bar and trip the stop motion. This type of stop motion is shown in Figures 10 to 20, and I have shown my float preventing mechanism associated therewith, but have not shown the drop wires in any of the figures except Figure 11 where I show the conventional drop wire mounted on one of the transverse bars, and my invention mounted on the other of the transverse bars which will be later explained.

In this modified form of my invention the side frame members of the loom are indicated by the reference characters 101 and 102, and at the top of the frame members 101 and 102 brackets extend inwardly in which bolts 103 and 104 are secured, and on which bolts the bars which support my invention and also which support the conventional drop wires are secured, which bars are indicated by the reference character 105, said bars having notches 106 and 107 therein which are adapted to be engaged by said bolts to hold the bar 105 into position. The bars in the conventional stop motion are of approximately the thickness of the point 108 as shown in Figure 10, but on the bar which carries my float preventing means I cut out the central portion of this bar to allow vertical movement of rod 109 without interfering with the conventional drop wires which are associated with this bar 105. This rod 109 is mounted in brackets 110 and 111 which are secured to the bar 105 by means of screws 112 and 113, and these brackets 110 and 111 are closed at their outer ends to prevent lateral movement of rod or wire 109. Along the bar 105 in addition to the regular drop wire mechanism I mount a plurality of my float preventing means which consists of the member 115 which has a hole 129 therein through which bar 105 passes. This member 115 has guides 116 and 117 thereon and in the upper end thereof a portion 118 is punched out on three of its sides from the member 115 and is turned at a right angle to 115, and has an inwardly sloping shoulder portion 119 thereon. On the other side of this member 115 from that shown in Figure 16, I have the same crimped inwardly to form a channel 120 which has the opened portion 121 to permit the bar to slide upwardly with relation to the member 115. In this channel 120 I mount the drop wire member 122 which has a hole 123 therethrough, through which the bar 105 passes. This elongated hole is of greater height than the bar 105 so as to allow vertical movement of member 122 with relation to bar 105. This member 122 also has a hole 124 therethrough, through which the wire 109 is adapted to pass. This member 122 near the upper end thereof has a portion 125 punched on three sides and bent at right angles, and on the upper end of this portion 125 we have the outwardly sloping shoulder 126. The drop wire 130 is slid-

ably mounted on the front face portion of the member 115 as shown in Figure 16, and is encased by the retaining members 116 and 117. This member 130 has the elongated slot 131 therein which is adapted to have the bar 105 and the rod 109 passed therethrough, and this member 130 is adapted to have the upper portion 133 normally held on top of an inwardly sloping shoulder 119 to hold the same in elevated position. When the thread 134 becomes too taut at any point along the rod 109 it will pull the member 122 upwardly and will cause the shoulder 126 to raise member 130 upwardly above the top of the inwardly sloping shoulder 119 and the outwardly sloping shoulder 126 will push this member 130 outwardly and cause the member 130 to drop downwardly between the stop motion mechanism which I shall now proceed to describe.

This stop motion mechanism consists of the fixed bars 142 and 143 which are secured to the lugs 140 and 141 by means of screws 144 and 145. The shaft 146 is mounted at its ends in bearings 148 and 149, and has the crank arms 150 and 151 thereon, which are secured to rods 153 and 154 which are pivotally connected to the crank arms 150 and 151 as at 155 and 156, said arms 153 and 154 projecting downwardly to the conventional stop motion mechanism. The rod 146 has the upwardly projecting arms 160 thereon which are integral with the serrated elongated bar 161. This bar 161 oscillates laterally and when it has a full swing over near the bars 142 and 143 it causes a projection which is not shown to swing clear of a cam on the main drive shaft, but when the regular stop motion drop wires 165 or the float preventing wire 130 drop downwardly between the bar 161 and either of the bars 142 or 143 it prevents this bar 161 from oscillating its full stroke, and therefore causes a portion of the mechanism associated with rods 153 and 154 to be engaged by a cam on the main drive shaft which pushes this mechanism away from the main drive shaft and operates stop motion mechanism to stop the loom by operating in most instances the regular shipper lever.

In the structure shown in Figures 1 to 9 inclusive, I have shown weights 62 on the wire or rod 58, to hold 58 in lowered position normally, to prevent said rod 58 from working upward during the weaving operation due to the vertical movement of the drop wires, and although I have shown only two weights 62 I desire it to be understood that any desired number of weights may be placed on rod 58 as may be necessary to hold the same normally in lowered position.

In Figures 10 to 20 inclusive I have similar weights 162 on rod 109 which act in the same manner as weights 62 in the structure shown in Figures 1 to 9 inclusive.

In the drawings and specification I have set forth a preferred embodiment of my invention, and although specific terms are employed they are used in a generic and descriptive sense only, and not for purposes of limitation, the scope of the invention being set forth in the appended claims.

I claim

1. A float preventive means in a loom comprising additional drop wires associated with the conventional stop motion in a loom having conventional drop wires, means associated with the conventional stop motion operable to automatically drop one of the additional drop wires to operate the stop motion mechanism when any portion of the warp between the drop wires and the woven part of the fabric in the loom becomes intermingled.
2. In a loom, a stop motion, said stop motion comprising a plurality of notched bars slidable with relation to each other, stop motion mechanism associated with said bars adapted to stop the loom when said bars are locked together, conventional drop wires mounted on said bars, a plurality of other drop wires associated with said bars, means for raising the other drop wires, a transversely disposed rod passing through the means for raising the other drop wires, said transversely disposed rod being adapted to pass immediately above the warp in the loom, said transversely disposed rod when raised being adapted to cause at least one of the other drop wires to fall and operate the stop motion means when any portion of the warp in the loom becomes too taut.
3. In a float preventer for looms, a conventional stop motion comprising relatively moving notched bars, a bracket member secured in said loom and having a portion thereof extending in vertical alignment with a set of said stop motion bars, a vertically disposed channel member in said bracket, a projection extending from one side of said bracket, a drop wire adapted to be normally sustained in elevated position by said projection, a member slidably mounted in said channel member and having a projection extending through said bracket member and through said drop wire, said slidably mounted in said channel having a hole therein, a transversely disposed rod adapted to penetrate the hole in said member slidably mounted in said channel, said rod and said member associated therewith being adapted to be raised when too great a tension is applied to the warp to cause the drop wire to fall downwardly to operate the stop motion mechanism.
4. In a stop motion and float preventing mechanism in a loom, a plurality of transversely disposed bars in said loom, an oscillating bar mounted below said transversely disposed bars, two fixed bars mounted below
5. In a loom having a conventional stop motion of the oscillating bar type, a plurality of transversely disposed bars having a plurality of drop wires slidably mounted thereon, said drop wires being adapted to be held in raised position by the warp threads, a plurality of other drop wires slidably mounted on said transversely disposed bars, a plurality of vertically sliding members mounted on said transversely disposed bars, a transversely disposed rod adapted to penetrate this vertically sliding member, said rod being adapted to be raised upwardly by an increased tension on the warp thread to release the other drop wires to allow them to drop downwardly and to operate the stop motion mechanism when any portion of the warp threads have a tension exerted thereon which is above the normal tension.
6. In a stop motion mechanism for looms, a float preventing mechanism associated with said stop motion mechanism, a plurality of drop wires and means for holding them normally in elevated position, means operable by an increase in the tension of any one of the warp threads to cause said drop wires to fall downwardly to operate the stop motion mechanism.
7. In a mechanical stop motion for looms, float preventing mechanism associated with said stop motion mechanism, said float preventing mechanism comprising a plurality of drop wires normally held in elevated position, a plurality of slidable members associated with said drop wires, a transversely disposed rod associated with said slidable members, said slidable members and the transversely disposed rod being adapted to

said sets of bars, said oscillating bar being adapted to swing a full stroke, a plurality of drop wires mounted on said transversely disposed bars and adapted to be sustained in upward raised position by means of the tension of the warp, said drop wires being adapted to fall downwardly when a warp thread becomes broken to prevent the oscillating member from having a full swing to cause the loom to be stopped, other means associated with said first named drop wires comprising a vertically disposed member on one of said bars, a vertically disposed channel member in said member, a drop wire adapted to be normally sustained in raised position by a projection, a member slidably mounted in said channel and having a projection extending in close proximity to the normally raised drop wire, a transversely disposed wire adapted to penetrate a hole in said slidable member, said wire being adapted to have the warp threads placed immediately therebeneath, said wire and sliding member being adapted to be raised upwardly by an increased tension on the warp to cause the last named drop wire to fall into the stop motion mechanism to stop the loom.

8. In a loom having a conventional stop motion of the oscillating bar type, a plurality of transversely disposed bars having a plurality of drop wires slidably mounted thereon, said drop wires being adapted to be held in raised position by the warp threads, a plurality of other drop wires slidably mounted on said transversely disposed bars, a plurality of vertically sliding members mounted on said transversely disposed bars, a transversely disposed rod adapted to penetrate this vertically sliding member, said rod being adapted to be raised upwardly by an increased tension on the warp thread to release the other drop wires to allow them to drop downwardly and to operate the stop motion mechanism when any portion of the warp threads have a tension exerted thereon which is above the normal tension.

9. In a stop motion mechanism for looms, a float preventing mechanism associated with said stop motion mechanism, a plurality of drop wires and means for holding them normally in elevated position, means operable by an increase in the tension of any one of the warp threads to cause said drop wires to fall downwardly to operate the stop motion mechanism.

10. In a mechanical stop motion for looms, float preventing mechanism associated with said stop motion mechanism, said float preventing mechanism comprising a plurality of drop wires normally held in elevated position, a plurality of slidable members associated with said drop wires, a transversely disposed rod associated with said slidable members, said slidable members and the transversely disposed rod being adapted to

be raised upwardly by an increase in the tension of the warp thread to cause said drop wire to drop downwardly to operate the stop motion mechanism in the loom.

8. In a float preventer for looms, said float preventer being adapted to cooperate with the conventional mechanical stop motion in a loom, a plurality of vertically disposed guiding members associated with said stop motion mechanism, a drop wire adapted to be held in elevated position by said guiding members, a sliding member mounted in each of said guiding members, a transversely disposed rod associated with said sliding members, said rod and at least one of said sliding members being adapted to be raised upwardly by an increase in the tension of the warp threads to cause the drop wires to be dislodged from their elevated position to fall downwardly to operate the conventional stop motion mechanism in the loom.

In testimony whereof I affix my signature.
LAURENCE E. BLACKMAN.
